Inventor

William Lawrence,

By his Attorney

John S. Dewey.

UNITED STATES PATENT OFFICE.

WILLIAM LAWRENCE, OF WORCESTER, MASSACHUSETTS.

BRAKE-SHOE.

SPECIFICATION forming part of Letters Patent No. 432,277, dated July 15, 1890.

Application filed May 12, 1890. Serial No. 351,367. (No model.)

To all whom it may concern:

Be it known that I, WILLIAM LAWRENCE, a citizen of the United States, residing at Worcester, in the county of Worcester and State 5 of Massachusetts, have invented certain new and useful Improvements in Brake-Shoes; and I do hereby declare that the following is a full, clear, and exact description thereof, which, in connection with the drawings making a part of this specification, will enable others skilled in the art to which my invention belongs to make and use the same.

My invention relates to brake-shoes adapted especially to be applied to horse and electric street-railway cars for engaging the track-rail to act as an emergency brake.

The object of my invention is to provide a strong, durable, and effective brake-shoe to be used on cars for engaging the track-rail 20 and checking the speed of the car and holding the same on steep grades and on slippery and icy track-rails, where the ordinary wheel-brakes will not be effective and will not prevent the wheels from sliding upon the tracks.

My invention consists in certain novel features of construction and operation of a brake-shoe, as will be hereinafter fully described, and the nature thereof indicated by the 25 claims.

My invention relates simply to the brake-shoe proper, which may be attached to a car in any ordinary or well-known way.

Referring to the drawings, Figure 1 is a side elevation of my invention, showing the 30 brake-shoe attached to a car and provided with means for operating the same. Fig. 2 represents, on a much enlarged scale, a central longitudinal section of the brake-shoe shown in Fig. 1. Fig. 3 is a plan view of the 35 brake-shoe with the cap-piece and holding-sections removed. Fig. 4 is a vertical cross-section taken at line α α , Fig. 2. Fig. 5 represents, on a reduced scale, a perspective view of the several parts of the brake-shoe detached from each other.

In the accompanying drawings I have 40 shown in Fig. 1 my improved brake-shoe attached to a car-frame and provided with means for operating the same to cause said 45 brake-shoe to engage the track-rail and to be disengaged therefrom.

The means for operating the brake-shoe

shown are fully described and set forth in Letters Patent of the United States, granted to G. O. Kane, No. 396,876, and therefore it 55 is not necessary to describe the same herein, as I make no claim to said means for operating the brake-shoe, but have simply shown the same to more fully illustrate the nature and application of my invention. Any other 60 manner of attaching my brake-shoe to the car and any other means for operating the same may be used, if preferred.

Referring now to the brake-shoe itself of my invention, 1 is the frame, preferably made 65 of cast metal and of the shape and form shown in the drawings. The frame 1 consists of the two sides 2, connected together by diagonal cross-pieces 3, and having open diagonal slots 4 extending between said cross-pieces 70 3. The sides 2 have at each end an upwardly-extending ear or projection 2', provided with a vertical slot 5 therein. The central portions of the sides 2 are preferably made thicker and provided with upwardly-extending double 75 ears or projections 6, each ear having a hole 7 therein. Wedge-shaped adjustable and removable holding-sections 8 of metal are combined with the frame 1 by fitting the same into the diagonal slots 4. The lower edges 80 of said sections 8 extend below the lower surface of the frame 1, and are prevented from passing through said slots by reason of the upper part of said sections 8 being made wider than the lengths of the slots 4. (See 85 Fig. 4.)

The holding-sections 8 at each end of the brake-shoe are preferably rounded on their lower edge, as shown in Fig. 2, and the extreme end sections 8 are made a little shorter. 90

The removable sections 8 in the central part of the brake-shoe are made square upon their lower edges. (See Fig. 2.) After the removable sections 8 have been inserted in the slots 4 of frame 1 of the brake-shoe the block or 95 cap-piece 9, preferably made of the shape shown in the drawings, is placed between the sides 2 of the frame 1 and extends over the upper edges of the removable sections 8, as shown in Figs. 2 and 4.

The ends of the cap-piece 9 fit against the inner side of the ears 2', and thus any longitudinal motion of said cap-piece is prevented. The rods 10, which extend through the holes 100

7 of the ears 6, which rods are preferably provided with bushings 11, as shown in Fig. 2, serve to hold down the cap-piece 9 and retain the removable sections 8 in their proper positions in the frame 1.

The brake-shoe is connected with the toggle arrangement shown in Fig. 1 by the arms 12, pivoted at their lower ends in the slots 5 of the brake-shoe, and by the arms 13, pivoted at their lower ends to the rods 10, extending through the holes 7 in the ears 6 of the brake-shoe.

The advantages of my improved brake-shoe will be readily appreciated by those skilled in the art. By placing the holding-sections 8 at an angle so that they will extend diagonally across the track-rail I cause them to push off from the track any snow, ice, or other material thereon, and at the same time I present a greater bearing-surface to the rail; and, further, by making the holding-sections 8 adjustable and removable from the frame 1, I can substitute new holding-sections, when the old ones become worn from constant use, by simply removing the cap-piece 9.

It will be understood that the details of construction of the different parts of my improved brake-shoe may be varied from what is shown and described, if desired.

It is not necessary to make the holding-sections 8 wedge-shaped, and instead of the cap 9 other means may be employed for holding the sections 8 in the slots 4.

Having thus described my invention, what I claim as new, and desire to secure by Letters Patent, is—

1. As an improved article of manufacture, a brake-shoe consisting of a frame provided with diagonal slots therein and having wedge-shaped removable sections extending through said slots and held in place therein, substantially as set forth. 40

2. In a brake-shoe, the combination, with the frame having diagonal slots therein, of sections extending through said slots for engaging the track-rail with their lower surface, substantially as set forth. 45

3. In a brake-shoe, the combination, with the frame having diagonal slots therein, of removable sections extending through said slots, and means for holding said sections in said slots, substantially as set forth. 50

4. In a brake-shoe, the combination, with the frame adapted to be attached to the operating mechanism and provided with diagonal slots in the bottom thereof, of adjustable and removable wedge-shaped sections adapted to extend through said slots, and to extend diagonally across the rail-track to engage the same with their lower edges, and means for holding said sections in said slots, substantially as set forth. 55

WILLIAM LAWRENCE.
